DISPENSER FOR GRANULAR MATERIALS

Paul V. Jensen, 3731 NE. 68th Terrace,
Kansas City, Mo. 64119

Filed Apr. 19, 1973, Ser. No. 352,641

Term of patent 3½ years

Int. Cl. D7—01

U.S. Cl. D7—17

Fig. 1.

Fig. 2.

Fig. 3.

Fig. 4.

Fig. 5.

Fig. 6.

Fig. 7.

FIG. 1 is a side elevational view of a dispenser for granular materials showing my new design;

FIG. 2 is a rear elevational view thereof;

FIG. 3 is a top plan view thereof;

FIG. 4 is a front elevational view thereof;

FIG. 5 is a bottom plan view thereof;

FIG. 6 is a sectional view taken along line 6—6 of FIG. 5 in the direction of the arrows; and

FIG. 7 is an exploded perspective view thereof on a reduced scale.

I claim:

The ornamental design for a dispenser for granular materials, as shown and described.
